HOIST LINKAGE

James F. Healy, Chicago, Ill.

Application December 22, 1952, Serial No. 327,206

3 Claims. (Cl. 254—135)

This invention relates to a hoist linkage and more particularly to a hoist linkage utilizing a mast supported by a pivoted boom.

It is an important object of the present invention to provide a novel hoist linkage utilizing a boom which is pivotally movable to an off-center position to provide a favorable mechanical advantage during a hoisting operation.

It is a further important object of the present invention to provide a novel hoist linkage wherein the hoist mast serves to counterbalance the load during hoisting.

It is a further object of the present invention to provide a hoist linkage utilizing a tilting of the mast during hoisting to tend to lever the load in raising direction.

Other objects, features and advantages of the present invention will be readily apparent from the following description taken in conjunction with the accompanying drawings, in which:

Figure 1 is a more or less schematic elevational view of the hoist linkage according to the present invention prior to the commencement of a hoisting operation;

Figure 1a is a cross-sectional view illustrating the pivotal and sliding mounting for the mast;

Figure 2 is a top plan view of the structure of Figure 1;

Figure 3 is an elevational view of a movable fulcrum for use with a structure similar to that shown in Figure 1; and

Figure 4 shows a modification of the movable fulcrum shown in Figure 3.

As shown on the drawings:

While the invention has been illustrated somewhat diagrammatically, it will be appreciated that in practice the hoist linkage may be carried on a suitable tractor, and it will be further understood that the present invention may be utilized as a toy as well as a lifting device for other purposes.

As illustrated in Figure 1, the structure of the present invention may rest on a suitable supporting surface 8 and include a fulcrum member 9 secured to the surface 8. A support structure 10 may also rest on the surface 8 and be secured thereto, and the support structure 10 may carry a yoke 10' pivotally supporting a bearing sleeve 11 by means of pins 12. The sleeve 11 receives a mast 14 in sliding relation therein, and in practice, the sleeve is dimensioned to provide easy relative sliding movement in the sleeve. For supporting the mast 14 and for constraining the movement of the boom 15, a member which will be termed a motion impetus shank and which is indicated at 17, is pivotally secured to the fulcrum 9 by means of a shaft 18. The motion impetus shank 17 provides a web portion 20 for supporting the boom 14, and carries a shaft 16 pivotally mounting the boom 15. For constraining the boom 15 to pivot in the clockwise direction with the shank 17, the shank is provided with an abutment 21 engaging a web portion 22 of the boom.

The mast 14 is provided with an obliquely extending integral leg 25 which forms one side of a quadrilateral linkage. The linkage includes a member 26 pivotally attached at 27 to the mast 14, a leg 28 pivotally connected to the lower end of the leg 25 at 29, and a link 31 pivotally connected between links 26 and 28 by pins 32 and 33. The pin 33 may carry a roller 35 for riding on the web 20 of the shank 17, and the pin 32 may carry a roller 36 for riding on the vertical surface 37 of the support structure 10. The support structure may also

provide a stop member 40 for preventing clockwise rotation of the mast beyond the vertical position.

As best seen in Figure 2, the boom 15 may carry a motor 42 or other suitable drive means for rotating the shaft 43 journaled in the frame members 15a and 15b of the boom 15. Mounted between the frame members 15a and 15b on the shaft 43 is a cable take-up drum 44. At the opposite side of the boom on the shaft 43 is mounted a gear 46 cooperating with the curved rack 47 secured to the support structure 10. Referring to Figure 1, it will be observed that a cable is secured at one end to the right end of the boom as indicated at 50 and extends downwardly and around a pulley 52 carried by the fulcrum 9 and then upwardly and around a pulley 53 carried at the top of the mast 14. The cable then extends downwardly around a pulley 54 at the left end of the boom 15 and then rearwardly and around the drum 44. The left end of the boom 15 may be connected to an object 60 to be lifted by means of a chain 61.

The operation of the illustrated structure will now be understood. As the motor is started and drives the drum 44 in the counterclockwise direction, the cable 49 is placed under tension tending to pull the boom in a clockwise direction and the mast 14 downwardly axially of the pivot 12 of the sleeve 11. However, as the mast 14 rotates about 12 in the counterclockwise direction, the linkage 25, 26, 28 and 31 tends to elongate in the vertical direction to drive the shank 17 clockwise and the boom 15 clockwise also. At this time the gear 46 may be disengaged from the shaft 43 to allow the shaft 43 to rotate in the counterclockwise direction independent of the gear 46 as by means of an overrunning clutch (not shown).

It will be appreciated that as the boom 15 moves in the clockwise direction, the moment arm of the weight 60 relative to the pivot 18 progressively decreases, while the moment exerted by the mast 14 on the motion impetus shank 17 progressively increases, due to the vertical offset between the pivot 18 and the points of application of the force exerted by the weight 60 and by the boom 14 on the boom and motion impetus shank. If the weight of the mast and other structure carried at the right of the boom is sufficient in proportion to the weight 60, it will be appreciated that as the weight 60 is raised, a point will come where the structure at the right of the boom overbalances the weight 60, and the weight 60 will be raised independent of the motor 42.

After the weight 60 has been raised, the gear 46 may be locked against rotation in the counterclockwise direction by any suitable means, and the weight 60 then disconnected from the boom 15. The gear 46 in conjunction with the rack 47 will, at this time, support the weight of the mast and prevent further raising of the boom. The motor 42 may be reversible to rotate the gear 46 in the clockwise direction and thus to raise the boom at its right end and lower it at its left end to the position shown in Figure 1.

In Figure 3 is illustrated a movable fulcrum comprising a body portion 75 swivelly mounting a neck piece 76 for carrying a motion impetus shank 77. The shank 77 may be similar to that shown in Figures 1 and 2 with its bifurcated end 77a journaled on the shaft 78 carried by the neck 76. The body 75 may be supported by three legs 80 having rollers 81 carried thereby for easy moving of the fulcrum. It will be appreciated that the fulcrum 75 may be anchored adjacent a suitable support structure such as 10 in Figure 1 so as to be utilized in the structure of Figure 1.

Figure 4 illustrates a further movable fulcrum 82 for swivelly mounting a neck such as 76 in Figure 3. The fulcrum 82 may comprise a pair of curved body members 84 and 85 connected by cross pieces such as 86 and having wheels 88 at the lower ends thereof. The piece 86 may have an opening therein indicated at 89 for receiving the neck 76 of Figure 3.

It will be understood that modifications and variations may be effected without departing from the scope of the novel concepts of the present invention.

I claim as my invention:

1. A hoist linkage comprising a support structure in-

cluding a fulcrum, a boom mounted for pivotal movement in opposite directions relative to said fulcrum, a mast guided by said support structure for axial movement and disposed above one end of said boom, means for transmitting the weight of the mast to said one end of the boom, lifting cable means engaging the other end of said boom and the top of said mast, and take-up means below said mast for drawing in said cable means, the tension in said lifting cable means exerting a downward force on said mast and an upward force on said other end of said boom.

2. A hoist linkage comprising a support structure having a vertical surface, a fulcrum member carried by said support structure, a motion impetus shank having one end pivoted to said fulcrum member, a boom pivoted intermediate the ends thereof to a point on said shank intermediate the ends of said shank, said boom having one end adjacent said vertical surface and the other end away from said vertical surface, means engaging said shank and said boom to cause said shank and boom to rotate together as the shank pivots in the direction about said fulcrum member to raise said other end of said boom, a sleeve pivotally mounted by said support structure above said motion impetus shank, a generally upright mast having a straight portion slidably carried by said sleeve and having an angled offset foot portion extending downwardly from the lower end of said straight portion and angularly away from said vertical surface, a pair of links connected at one end to spaced points on said foot member and extending angularly toward said vertical surface, and a further link pivotally connected to the opposite ends of said first mentioned pair of links to define a quadrilateral linkage, said linkage having means at the lower corner thereof engaging said motion impetus shank and having means at the lateral corner thereof adjacent said vertical surface engaging said surface, pulley means carried by said fulcrum, pulley means

carried at the top of said mast, and pulley means carried at said other end of said boom, and cable means anchored at said one end of said boom extending downward and around the pulley means carried by said fulcrum, 5 upwardly around the pulley means carried by said mast, downwardly around the pulley means carried at said other end of said boom, and a take-up drum carried by said boom at said one end thereof receiving said cable from the pulley means at said other end of said boom, and means for driving said take-up drum to raise said other end of said boom.

10 3. A hoist linkage comprising a support including a fulcrum, a boom mounted for pivotal movement relative to said fulcrum in opposite directions, a generally upright mast, a pivotal mounting for said mast carried by said support and disposed above one end of said boom, said mast having a quadrilateral linkage including an angularly offset foot depending below said mast, means for transmitting the weight of the mast to said one end of the boom through said linkage, means constraining said linkage to extend in the vertical direction upon pivotal movement of said mast in one direction about said mounting, cable means including a portion extending over the top of said mast and downwardly to the other end 15 of the boom, and take-up means for taking up said cable to exert an upward force on said other end of said boom and a downward force on the top of said mast, whereby the mast tends to rock in said one direction to extend said linkage in the vertical direction to urge said one end of the boom downwardly and said other end of the boom upwardly.
